UNITED STATES PATENT OFFICE.

JOSEPH SYLVAN, OF CHICAGO, ILLINOIS.

VENTILATOR.

1,295,813.

Specification of Letters Patent. Patented Feb. 25, 1919.

Application filed October 4, 1918. Serial No. 256,788.

To all whom it may concern:

Be it known that I, JOSEPH SYLVAN, a citizen of the United States, and a resident of Chicago, in the county of Cook and State of Illinois, have invented certain new and useful Improvements in Ventilators; and I do hereby declare that the following is a full, clear, and exact description thereof, reference being had to the accompanying drawings, and to the letters of reference marked thereon, which form a part of this specification.

This invention relates to improvements in ventilators for roofs, skylights and the like, and consists of the matters hereinafter described and more particularly pointed out in the appended claims.

The object of the invention is to provide a ventilator of the kind described in my pending application, Serial Number 251,867, filed August 29, 1918, with a novel and improved means for increasing the updraft and at the same time preventing a downdraft.

The many advantages of the invention will appear as I proceed with my specification.

In the drawings:—

Figure 1 represents a perspective view of my improved ventilator with parts shown as broken away to more clearly show the interior construction of the same.

Fig. 2 represents a vertical section through the same, the plane of the section being indicated by the line 2—2 of Fig. 3.

Fig. 3 represents a horizontal section through the ventilator in a plane indicated by the line 3—3 of Fig. 2.

Fig. 4 represents a perspective view of an interior part of the ventilator and will be more specifically referred to later.

Fig. 5 represents a vertical, detail section which will also be more specifically referred to later.

Referring now in detail to that embodiment of the invention illustrated in the accompanying drawings:—7 indicates as a whole, the improved ventilator which is made of sheet metal. 8 indicates the upright, tubular stem of the ventilator which is attached in any suitable manner to a roof or skylight, and 9 indicates the conical cover or

top of the ventilator which is spaced a suitable distance above the top end of the stem 8. Said top is substantially rectangular in plan and is longer in one direction than the other, and has rounded corners.

55

10, 10 indicate opposed, upright end walls or weather shields, which are fixed at their top ends to the shorter ends of the cover or top and are held in suitable spaced relation with respect to the stem 8 by horizontal webs

60

11. The marginal side parts of the said upright walls 10, are curved transversely to conform to the rounded corners of said cover or top 9. The webs 11 act as barriers against upward air currents and also act as drain plates for such moisture as forms on the inner surfaces of said upright walls 10.

65

12, 12 indicate opposed, upright wing plates which are arranged in planes at right angles to the planes of said upright walls 10. 70 Said wing plates are of a width equaling the distance between the edges of the curved margins of the end walls 10 and have upright marginal flanges 13 which are fixed at their bottom ends to the stem 8 and at their top ends to the inner surface of the top 9, in a line spaced inwardly from the longer sides of said top.

75

The middle parts of the wing plates are flared outwardly from top to bottom, to 80 provide conduits 14 which lead into the interior of the ventilator above the top end of the stem. The bottom ends of said conduits provide entrance openings or mouths for the entrance and exit of air currents. To prevent the air entering through said mouths from passing directly into said stem, I provide baffles 15 and 16 which direct the air currents in a tortuous path upwardly above

85

said stem. The baffles 15 are attached to the bottom edge of the conduits 14 and extend inwardly toward the stem, while the other baffles 16 are attached to the top end of the stem and extend outwardly therefrom as shown in Fig. 5. The structure just described, is substantially the same as that shown in my pending application heretofore referred to.

90

Within the ventilator is a deflector member 17, shown in perspective in Fig. 4. This 100

deflector comprises two similar, divergent legs 18, 18 which are connected together at their top ends and diverge downwardly and outwardly from top to bottom. The top ends 5 of said legs, which are of a width approximating the diameter of the stem, are arranged in a plane extending transversely of the wing plates, and each leg tapers downwardly and in cross section from the top to 10 the bottom, from a substantially flat cross section at the top, to a transversely curved or U-shaped cross section. The bottom ends of the legs are fixed to the outer surface of the top end of the stem 8, in the longitudinal 15 median plane of the ventilator as a whole.

The operation of the improved ventilator is as follows. With an air current moving in a plane parallel to the end walls 10, a part 20 of said air will enter the ventilator through the openings defined by the edge of the curved margins of the end walls and the edges of the upright marginal flanges of the wing plates, and pass out of the ventilator through the corresponding openings on the 25 opposite side of the ventilator. A part of this air is deflected by striking the bottom ends of the legs of the deflector, so that an air current is produced across the top of the stem. The current of air thus passing 30 through the ventilator will produce an up-draft in the stem and draw the air out of the room of the building to which the ventilator is applied.

If any of the moving currents of air enter 35 the ventilator through the mouth of the conduits 14 provided by the wing plates 12, said air currents are caused to follow a tortuous path, by the baffles and to be directed against the inner face of the conduit 40 14. This will direct the air current upwardly toward the cover or top 9 of the ventilator. The cover or top will then direct said air current downwardly against the legs of the deflector which will divide 45 said current into two parts and direct them into the main body which is passing horizontally through the ventilator. The deflector 17 thus acts to deflect the downward air current outwardly and prevents it from entering or blowing down the stem. 50 As the air current follows up the inner surface of the conduit, it will establish a suction action at that part of the top end of the stem, not affected by the current of air 55 passing horizontally through the ventilator, so that the suction action as a whole is felt over substantially the whole area defined by the stem.

Should any moisture collect on the inner 60 surface of the top or cover, due to condensation, this moisture will drain toward the edges of the top and either pass downwardly on the inner faces of the conduits 14 to be discharged through the mouths

thereof, or downwardly to engage the inner 65 face of the end walls 10 and from there onto the plates or webs 11, to be discharged outside of the ventilator. If the moisture of condensation collects too rapidly at the middle of the ventilator top, it will fall 70 onto the top of the deflector and be directed downwardly by the legs thereof, onto said plates or webs, to be discharged as before mentioned.

Thus, this deflector adds to the efficiency 75 and improves the operation of the ventilator by deflecting the air across the top of the stem to increase the updraft and by preventing the air currents from entering the stem to produce downdrafts through the 80 stem.

While in describing my invention, I have referred to certain details of construction and arrangement of parts, I do not wish to be limited thereto except as pointed out in 85 the appended claims.

I claim as my invention:

1. A ventilator for roofs, skylights and the like, comprising in combination with an upright, tubular stem, a cover spaced vertically above said stem, upright, opposed wind shields and wing plates attached to said stem and cover, the margins of said wind shields and wing plates being spaced apart to provide passageways into and out 90 of the ventilator, and a deflector member in said ventilator comprising a plurality of legs connected together at their top ends and engaged against the outer edge of the stem at their bottom ends, said deflector being adapted to deflect the down draft from 95 the cover of the ventilator to points beyond and without the top end of the stem.

2. A ventilator for roofs, skylights and the like, comprising in combination with an upright, tubular stem, a cover spaced vertically above said stem, upright, opposed wind shields and wing plates attached to said stem and cover, the margins of said wind shields and wing plates being spaced apart to provide passageways into and out 100 of said ventilator, and a deflector member in said ventilator comprising two oppositely disposed, diverging legs which are connected at their top ends and are there of 105 a width approximating the diameter of the stem, the said legs tapering downwardly from a substantially flat cross section at the said top ends to a narrower, transversely curved, U-shaped cross section at their bottom ends, said bottom ends being attached to the outer edge of the stem, said legs being adapted to deflect the down drafts from 110 the cover of the ventilator to points beyond and without the top end of the stem.

3. A deflector member for ventilators of the kind described, comprising two oppositely disposed legs which are connected to 115

gether at their top ends and diverge downwardly and outwardly from said top ends, each leg tapering from top to bottom from a substantially wide, flat cross section to a 5 narrower, transversely curved, U-shaped cross section.

In testimony that I claim the foregoing

as my invention, I affix my signature, in the presence of two witnesses, this 28th day of September, A. D. 1918.

JOSEPH SYLVAN.
